United States Patent Office

Des. 184,569
Patented Mar. 10, 1959

184,569

FLOWER HOLDER

James M. King, Los Angeles, Calif.

Application September 26, 1956, Serial No. 43,098

Term of patent 14 years

(Cl. D35—3)

FIG. 1.

FIG. 2.

FIG. 3.

FIG. 4.

Fig. 1 is a top plan view of a flower holder embodying my new design;

Fig. 2 is a side elevation of Fig. 1 as viewed from either side;

Fig. 3 is a bottom plan view; and,

Fig. 4 is an end elevation of Fig. 1 as viewed from either side.

I claim:

The ornamental design for a flower holder, substantially as shown.
